UNITED STATES PATENT OFFICE

JAMES A. BOWER, OF ANDERSON, INDIANA, ASSIGNOR TO NATIONAL TILE COMPANY,
OF ANDERSON, INDIANA, A CORPORATION OF OHIO

TILE HANDLING MACHINE

Application filed April 13, 1929. Serial No. 354,904.

My invention relates to a machine for handling tiles of any of the various stages of the processes of manufacture or finishing, and particularly for stacking tiles in a predetermined manner as they are received green from the press, and it is an object of the invention to provide a machine which will so handle and stack the tiles that they may be moved in multiples by an operator without injury thereto and with great facility and likewise in a manner to permit them to be inspected during the stacking operation, all as will be hereinafter more fully described and claimed.

Broadly stated, my invention comprises a belt conveyor for receiving green tiles from a press, not shown, from which conveyor the tiles are placed in stacked relation upon a table with means for lowering the table successively in a step by step manner as each tile is deposited thereon. A reciprocating carriage is provided for pushing the tiles one at a time off the conveyor onto the table, and another reciprocating carriage is provided for pushing the stacked tiles off the table onto a receiving board which is adapted to be placed by an attendant in a kiln for firing.

Referring to the accompanying drawings, which are made a part hereof and on which similar reference characters indicate similar parts,

Figure 1 is a side elevation, illustrating one application of my invention,

Figure 2, a front end elevation,

Figure 3, a top plan view,

Figure 4, a fragmentary detail section taken on line 4—4 of Figure 1,

Figure 5, a fragmentary detail,

Figure 6, a fragmentary detail taken on the line 6—6 of Figure 2, and

Figure 7, a fragmentary detail perspective of a bracket and portion of a pusher plate.

In the drawings reference character 10 indicates upright frame members connected by lower horizontal side bars 11, intermediate horizontal side bars 12, and cross bars 13 and 14. A conveyor belt 15 extends around a pulley 16 mounted upon a transverse shaft 17, and upon the opposite end of the conveyor green tile 18 are deposited from a press,

not shown. The upper run of the conveyor belt is supported on its under side by a plate 19, so that the tile may travel in a horizontal plane from the receiving to the discharge end of the conveyor.

In spaced relation to the discharge end of the conveyor is mounted a table 20 supported upon an upright rod or bar 21 held in upright position by brackets or bearings 22, said rod being preferably polygonal in cross section to prevent rotation of the table. The rod 21 is provided at its lower end with a roller 23 for co-operation with actuating mechanism hereinafter more particularly described.

The table 20 is preferably provided with a depending hub 24 having a socket for the reception of the upper end of the rod 21, a set screw 25 being utilized for securing the hub on the rod. The table is provided with an upper facing 26 of tile, in order that the tile may be uniformly handled. The first and second tile otherwise would be deposited on dissimilar surfaces, but the facing 26 forms a surface for the first tile similar to that upon which the second tile will be deposited. Between the upper run of the conveyor and the table upon which the tile are adapted to be deposited from the conveyor is fixed a filler plate 27, which spans the gap between the belt and the table. Thus, as the tile are advanced on the conveyor they will be deposited onto the table 20, and I provide means hereinafter described, for lowering the table corresponding to the thickness of the tile, so that as the tile are deposited on the table one by one the table will lower in a step by step manner to receive each tile.

Power for operating the machine is supplied by a sprocket chain 28 and sprocket 29 on a transverse shaft 30 and another sprocket 31 on said shaft drives a sprocket chain 32 which engages a sprocket 33 fixed to a shaft 34 beneath the conveyor belt 15. On the shaft 34 there is another sprocket 33', which through the instrumentality of a chain 35 and a sprocket 36 on the pulley shaft 16 drives the conveyor. A pinion 37 fixed on the shaft 30 drives a relatively large gear 38 (6 to 1 ratio) on a shaft 39 supported in bearings 40 on the frame.

The shaft 39 has a cam wheel 41 fixed thereon which engages roller 23 on the lower end of the polygonal table carrying rod 21. The cam wheel 41 has stepped peripheral surfaces 5 faces 42 to 47 inclusive cut on uniformly varying radii to permit the rod 21 and table supported thereby to lower in a step by step manner as the roller on the lower end of the rod engages the respective surfaces on the cam wheel. The differences in radii of the various peripheral surfaces is equivalent to the thickness of a single tile, so that the table will move downward just enough to accommodate the next tile to be placed upon the stack until the table is completely filled and the roller 23 rests on the peripheral surface 47 having the shortest radii or nearest the center of the cam wheel. When in this position the tile are transferred from the table onto the receiving board 48, from which they are adapted to be removed by an attendant and put in a container for treatment in the kiln.

In order to transfer the tile one at a time from the conveyor onto the table, I provide a reciprocating carriage 49 provided with spaced rollers 50 at each side of the same located in U-shaped channel members 51 and 52. At the front end of the carriage 49 is a cross rod 53 on which is pivoted a pusher plate 54. The pusher plate 54 has a lug 55 on its rear side, by means of which the plate is normally held in a depending substantially vertical position at right angles to the conveyor belt in a position to engage a tile. A spring 56 normally maintains the plate in the depending condition described but will yield to permit the plate to swing upward on striking the adjustable stop screw 70 and permit the next tile to be stacked to pass under the plate without injury. The front side of the pusher plate is faced with soft rubber 57 so that the tile will not be injured as the pusher makes contact with the tile.

The carriage 49 is reciprocated by a rocker arm 58 pivoted at 59 on the frame bar 12, said rocker arm having a roller 60 at its lower end which is engaged by a cam 61 on the shaft 30 so that at each revolution of the shaft the rocker arm will be reciprocated to move the carriage forwardly and to return the same to its retracted position. The rocker arm 58 is provided at its upper end with a pair of yoke forming arms 62 and 63 each of which is provided with opposed spaced plates 64 between which are disposed sliding blocks 65 which form journals for a shaft 66 supported by spaced uprights 67 on the carriage 49. A spring 68 is anchored to a bracket 69 on the frame and to the rocker arm and serves to return the carriage to its retracted position, as shown in Fig. 1. The tile is pushed off the conveyor belt at such a speed that the carriage will be returned to its original clear position (Fig. 1) before the subsequent tile

has reached the position where it would be damaged by the rear side of the pusher plate. In order to maintain the pusher plate out of the way of tile passing under it when the carriage is in retracted position, I provide an adjustable stop screw 70 threaded in a cross bar 71 attached to the rails or channels 51 and 52 in which the carriage rollers are mounted.

I have described means for conveying the tile and for transferring it from the conveyor to the table which lowers as each tile is received, and will next describe the mechanism for pushing the stacked tile off the table onto the mounting board. This device comprises a carriage 72 having rollers 73 at its opposite sides disposed in channel members which form a track for the carriage. A pair of depending arms or brackets 74 support a removable pusher plate 75 having a soft facing 76 of rubber or the like adapted to contact with the stack of tile on the table. The lower ends of the depending arms are bent up to receive the pusher plate which is adapted to be elevated by the upward movement of the table if the carriage has not reached its retracted position. The raising of the pusher plate will prevent any damage being done to the machine. The carriage 72 is operated by means of a rocker arm 77 having a roller 78 on its lower end, which is engaged by a lobe 79 of a cam 80 on the cam wheel shaft 39. The upper end of the rocker arm is provided with a pair of yoke arms 81, one of which is disposed at each side of the machine and each yoke arm has spaced plates 82 which receive a sliding block 83 which forms a journal for a shaft 84 held upon up- rights 85 on the carriage 72.

The machine is timed to operate in conjunction with a wall tile press so that as each tile is carried along by the conveyor it will be pushed off the same onto the depressible table at such a speed that the carriage will make the forward and backward movement in time to reach the clear position shown in Fig. 1 only that the pusher will be out of the way to permit the tile to pass beneath the same to a position to be pushed off the conveyor. At the same time for each movement of the carriage the cam wheel turns a sufficient distance to lower the table the thickness of one tile until the stack of tile is complete, whereupon the lobe 79 engages the roller 78 and operates the rocker arm 77 and carriage 72 to push the stack of tile onto the mounting board. This cycle of operation is repeated during the operation of the machine.

It will be obvious to those skilled in the art that various changes may be made in my device without departing from the spirit of the invention, and I, therefore, do not limit myself to what is shown in the drawings and

described in the specification, but only as set forth in the appended claims.

Having thus fully described my said invention, what I claim as new and desire to secure by Letters Patent, is:

1. A machine of the class described comprising a conveyor, a table for receiving articles conveyed, primary discharging means for discharging articles singly from the conveyor onto the table, secondary discharging means for discharging articles from the table, a pair of associated shafts, a connection between the shafts for causing one to make several revolutions to each revolution of the other shaft, a connection between the rapidly revolving shaft and the primary discharge means, a connection between the slowly revolving shaft and the secondary discharge means, and a cam on the slowly rotating shaft having its periphery engaging a connection to the table, said periphery being cut along stepped radii to cause a gradual lowering of the table the arrangement being such that a plurality of articles will be discharged from the conveyor onto the table and the table lowered to cause the articles to be disposed in stack formation and the stack discharged from the table by the secondary conveyor, substantially as set forth.
2. In a tile handling machine the combination of a conveyor, a table for receiving tile from the conveyor, means for transferring the tile from the conveyor to the table, a continuously revolving variable cam having its periphery cut into a plurality of tracks, each track being closer to the center of the cam than the one next preceding it to provide step-down surfaces, the table having a depending post having its lower end resting upon the said cam for lowering the table in step-by-step manner as the tile are deposited thereon, substantially as set forth.

3. In a tile handling machine the combination of a conveyor, a table for receiving tile from the conveyor, means for transferring the tile from the conveyor to the table, a continuously revolving variable cam having its periphery cut into a plurality of tracks, each track being closer to the center of the cam than the one next preceding it to provide step-down surfaces, the table having a depending post having its lower end resting upon the same cam for lowering the table in step-by-step manner as the tile are deposited thereon, and means for discharging the tile from the table, substantially as set forth.

4. A machine for handling articles for arranging them in stacked formation comprising a conveyor, a table for receiving the articles from the conveyor, means for discharging the articles one by one from the conveyor to the table, a continuously revolving cam having its peripheral surfaces cut to provide cams each of which lies in an arc of a circle smaller than the one next preced-

ing it, a post secured to the lower portion of the table having its lower end in engagement with the periphery of the cam for lowering the table an amount corresponding to the thickness of each article so that the receiving surface of each article discharged from the conveyor will be substantially in the plane of the conveyor until a predetermined number of articles are arranged in a stack, means for discharging the stack of articles as a unit and a rapid return surface on said cam for causing the table to rise quickly to a position at which it may receive another stack of articles, substantially as set forth.

5. The combination of a continuously moving belt carriage for receiving green tile from a tile press, a table for receiving the tile, a cylindrical cam having its peripheral surface formed of a plurality of cylindrical surfaces each of which lies nearer the center of the cam than the one next preceding it, a post secured beneath said table and having its lower end resting upon the said cam for lowering the table in a step-by-step manner as the cam is rotated to cause the tile to be deposited in a superimposed relation to form a stack, a carriage having means engageable thereon with the tile for pushing them one at a time from the conveyor to the table, a cam for operating said carriage, said reciprocable carriage operating at a greater speed than that of the conveyor, a second reciprocable carriage for pushing the stacked tile as a unit from the table to a receiving board, means for actuating said carriage at a speed to cause a plurality of operations of the first carriage to one of the second, substantially as set forth.

In witness whereof, I have hereunto set my hand at Anderson, Indiana, this 8th day of April, A. D. nineteen hundred and twenty-nine.

JAMES A. BOWER.
